UNITED STATES PATENT OFFICE

2,356,509

MECHANICAL PENCIL AND METHOD OF
MAKING SAMEFrank C. Deli, Chicago, Ill., assignor to Autopoint
Company, Chicago, Ill., a corporation of Illinois

Application September 27, 1943, Serial No. 503,937

16 Claims. (Cl. 120—18)

This invention relates to mechanical pencils and to a new method of making the same, and is an improvement over the invention of Patent No. 2,033,687 granted to me March 10, 1936. In that patent there is provided in the tip a metallic tube, generally made of brass or similar soft metal, in the walls of which is formed, by spinning or otherwise forcing the metal inwardly in a machine, a helical indentation constituting a screw thread extending longitudinally throughout the length of the tube. Mounted within said tube is a plunger, or lead propeller, having one or more lugs or lateral projections that enter said thread to travel therealong and propel a lead through the tip, as the tip is rotated in a predetermined direction with relation to the barrel.

Since, for war reasons, brass or other suitable metal tubing is not available for commercial manufacture, the present invention eliminates the need for the same, and yet provides for the spiral trackway to receive the propeller lugs for propelling a lead, said trackway being fixed in the tip to rotate therewith as the tip is rotated relatively to the barrel. To this end I have provided a coil spring of the required size and pitch, and a novel arrangement of the same in the tip, so that the brass or similar metal tubing referred to above is eliminated.

I have also provided a novel arrangement of thin metal tube, of a metal more readily obtainable, so formed as to provide a more efficient rotatable and removable friction grip between the tip and the barrel, and to hold the coil spring operative in position therein, said thin metal tube and coil spring being fixed to the tip to rotate therewith.

In addition to eliminating the need of using tubing made of brass or other suitable similar metal so vitally needed in war work, I have, by the use of the coil spring referred to above, accomplished several very valuable advantages. By reason of the coil spring being fixed to the tip only at the forward end portion of the spring, the major portion of the coil spring, including its rear end, being unattached to its surrounding thin metal tube, this unattached major portion being of springy nature due to its shape, although rigid enough to normally propel a lead, will yield should the propelling mechanism become jammed, and thus avoid a breakage of parts that might otherwise occur. In other words, this coil spring construction affords a flexibility and safety of operation as well as a normal positiveness of action, not possible in the old form of construction.

Another considerable advantage of the coil

spring of the present invention is that due to the major portion of the coil spring being unattached to any surrounding parts, a much greater space is provided around the wire of the individual coils, to receive and hold lead dust as the same is shaved off from the leads as they pass through the inner bore of the coil spring during operation of the pencil. Also any such lead dust as might accumulate from time to time around the coils has a much better chance to be shaken loose and out of the tip when inserting a new lead, by reason of the rear end and major portion of the coil spring being unattached.

Also considerable labor cost is saved by the fact that the major part of the length of the coil spring is not attached to any other part, it being secured within the surrounding tube and to the tip only at its forward portion.

A further advantage of this coil spring construction is that, due to its open formation, the propeller lugs may more readily pass into the rear open end of the coil of the coil spring, when the propeller is being inserted into the tip after a new lead has been added.

Additional advantages possessed by the coil spring arrangement described herein are economy of manufacture, efficiency of operation, yieldable but positive action and ease and effectiveness in assembling.

Other objects, advantages and capabilities will later more fully appear.

My invention further resides in the combination, construction and arrangement of parts illustrated in the accompanying drawings, and while I have shown therein a preferred embodiment, I wish it understood that the same is susceptible of modification and change without departing from the spirit of my invention.

In the drawings:

Figure 1 is an enlarged side elevation of a mechanical pencil embodying my invention, although other external shapes may be used if desired.

Fig. 2 is a still more greatly enlarged fragmentary vertical longitudinal section taken on a median plane through the tip, propelling mechanism and lower end portion of the barrel.

Fig. 3 is an enlarged longitudinal section on a median plane through the metal portion of the tip, the friction grip tube for rotatably holding the tip to the barrel, and the spiral trackway coil spring.

Fig. 4 is an enlarged side elevation of the friction grip tube looking at the side having the short slit.

Fig. 5 is a view similar to Fig. 4 but looking at the opposite side.

Fig. 6 is an enlarged side elevation of the metal portion of the forward end of the tip.

Fig. 7 is an enlarged side elevation of the coil spring of my improved tip construction.

Fig. 8 is a longitudinal section of the friction grip tube taken on the line 8—8 of Fig. 4.

Fig. 9 is a longitudinal section of the friction grip tube taken on the line 9—9 of Fig. 8.

Fig. 10 is a longitudinal section on a median plane through the forward tip portion of Fig. 6.

Fig. 11 is an enlarged transverse section through the friction grip tube taken on the line 11—11 of Fig. 8, showing the tube in slightly exaggerated expanded position before being inserted into the barrel.

Referring more in detail to the drawings, my improved pencil comprises a body portion or barrel 1 having at its lower end a reduced portion 2 tapered downwardly and inwardly, and forming with the barrel the annular shoulder 3 against which abuts the end 4 of the non-metallic portion 5 of the tapered tip 6. Portion 5 is preferably formed of a plastic material. The lower or forward end 7 of the tip is formed preferably of metal, and at its nose portion has a pair of oppositely positioned slits 8 to enable frictional gripping of the lead 9. The metal portion 7 of the tip at its upper or inner end is formed with a cylindrical collar 10 of smaller diameter than the largest diameter of the portion 7, these two parts being connected together by a shoulder portion 11.

As shown in Figs. 4, 5, 8 and 9, I have provided a tube 12 preferably of thin, black or other more readily available metal, and of an outside diameter to enable it to be inserted longitudinally into the cylindrical collar 10 until its lower end touches the inside walls of the lower tip portion 7, or not as desired, as will be understood in Figs. 2 and 3. Tube 12 is formed on one side, and extending longitudinally throughout its length and through the thickness of the wall, with a slit 13, while on its opposite side and 180 degrees removed from slit 13 is a shorter slit 14 which is closed at both ends. The metal on each side of slits 13 and 14 is resilient, and if desired may be bent slightly outwardly to enable a frictional gripping action when the parts are assembled and the tube 12 is pushed into the longitudinal bore 15 in the forward end of the barrel (see Fig. 2).

The bending slightly outwardly of the edge portions of the metal on each side of slit 13 will preferably be effected by inserting a key (not shown) of suitable shape into the appropriately shaped opening 13' (Fig. 5) and turning the same to bend said edges outwardly and if desired move the key a desired distance along the slit 13. Or other suitable means may be employed for this bending action. This slight outward bending of the metal along the edges of the slit 13 enables the resilient thin metal to be forced inwardly a slight distance when the tube 12 is forced with a slight push into the longitudinal bore 15 when applying the tip to the barrel. The shorter slit 14 on the opposite side of the tube aids in producing this resilient grip which grip is sufficient to hold the tip onto the barrel, enable its rotation with relation to the barrel, and enable the tip to be removed from the barrel for reloading when desired.

Inserted longitudinally within tube 12 is a coil spring 16, which before the parts are assembled

is longitudinally slidable therein. When the coil spring 16 and the tube 12 are assembled together and passed into collar 10 to the position shown in Figs. 2 and 3, the metal of collar 10 will be swaged or otherwise compressed inwardly to tightly grip the end of the tube therein, the adjacent portion of the coil spring 16 therewithin being, by the same swaging action, simultaneously gripped within tube 12, to be firmly held therein against either longitudinal or rotational movement at that portion within collar 10. As seen in Figs. 2 and 3, the coils of coil springs 16, at that portion within collar 10, will be slightly indented into the metal of tube 12 to more effectively hold these parts together. All of that portion of the coil spring lying within the tube 12 between the inner end of collar 10, and the inner or free end of this tube is, however, unattached to the tube, but is free to be sprung either longitudinally or rotationally by the lugs 17, 18 of the lead propeller 19 should these parts become jammed during operation of the pencil. Also this unattached feature of the coil spring provides ample space around the coils for deposit of lead dust which may be shaved off the leads during their forward feeding movement, which dust, from time to time, may be knocked out of the tube by tapping upon the end of the tip when there is no lead therein. Those coils which project forwardly of the forward end of tube 12 act to guide and laterally support the lead when its rear end passes beyond tube 12.

The upper or inner end of the propeller 19 is formed with a non-circular head to fit within a non-circular bore in the barrel (not shown) in the well known manner, for example as shown in my U. S. Patent 1,929,969, granted October 10, 1933, for "Mechanical pencil," to enable lead-feeding operation of the parts. The inner end of the coils of the coil spring being open enable a more free insertion of the propeller lugs 17, 18 thereinto, and a correspondingly greater certainty of operation when a new lead is inserted.

As will be understood from the above, rotation of the tip with relation to the barrel will cause a longitudinal movement of the propeller and a corresponding feeding movement of the lead. It will thus be seen that I have not only eliminated the need of brass tubing which is required in war work, but I have at the same time provided a more effective pencil in which the particular arrangement of the coil spring in the friction grip tube enables the rear and major portion of the coil spring to be unattached to the tube, thus providing a greater flexibility of operation with positive action, prevention of breakage of parts should the lead propelling mechanism become jammed, open coils at the inner end of the coil spring to more effectively receive the lugs of the propeller when reassembling the parts after insertion of a new lead, and an easier and more certain way of temporarily storing and later removing the lead dust shaved off from time to time from the leads during their passage through the tip.

The tube 12 may be rolled from flat, thin, sheet-metal to bring the side edges side by side but slightly spaced apart to give a frictional grip in the bore of the barrel, and in any appropriate manner form the closed ended shorter slit 14 in the opposite side either before or after rolling the sheet into tubular form as desired. The coil spring 16 may be formed of any suitable metal in any of the well known manners. The coil spring and tube are then assembled in the col-

lar 10 and swaged together as earlier described, the coil spring being so positioned in the tube that its rear end will extend substantially to the rear end of the tube in any unattached and yieldable manner for purpose hereinbefore pointed out.

Having described my invention, I claim:

1. In a mechanical pencil, a barrel, a tip rotatably mounted on the barrel, a metal nose on said tip, said nose having a rearwardly extending collar, a metal tube having its front end portion inserted into said collar, a coil spring within the tube, the collar tightly gripping the adjacent portion of the tube, and the last mentioned portion of the tube tightly gripping the adjacent portion of the coil spring, and a propeller having a lateral projection engageable between the coils of the coil spring to move the propeller longitudinally when the tip is rotated relatively to the barrel, and means for holding the propeller against rotation with relation to the barrel when the tip is rotated thereon.

2. In a mechanical pencil, a barrel, a tip rotatably mounted on the barrel, a metal nose on said tip, said nose having a rearwardly extending collar, a metal tube having its front end portion inserted into said collar, a coil spring within the tube, the collar tightly gripping the adjacent portion of the tube, and the last mentioned portion of the tube tightly gripping the adjacent portion of the coil spring, and a propeller having a lateral projection engageable between the coils of the coil spring to move the propeller longitudinally when the tip is rotated relatively to the barrel, the coil spring rearwardly of the collar being unattached to the tube, and means for holding the propeller against rotation with relation to the barrel when the tip is rotated thereon.

3. In a mechanical pencil, a barrel, a tip rotatably mounted on the barrel, a metal nose on said tip, said nose having a rearwardly extending collar, a metal tube having its front end portion inserted into said collar, a coil spring within the tube, the collar tightly gripping the adjacent portion of the tube, and the last mentioned portion of the tube tightly gripping the adjacent portion of the coil spring, and a propeller having a lateral projection engageable between the coils of the coil spring to move the propeller longitudinally when the tip is rotated relatively to the barrel, the coil spring rearwardly of the collar being unattached to the tube, the rearmost coil of the coil spring terminating in a free end to receive the projection of the propeller as it is threaded therewith, and means for holding the propeller against rotation with relation to the barrel when the tip is rotated thereon.

4. In a mechanical pencil, a barrel, a tip rotatably mounted on the barrel, a metal nose on said tip, said nose having a rearwardly extending collar, a metal tube having its front end portion inserted into said collar, a coil spring within the tube, the collar tightly gripping the adjacent portion of the tube, and the last mentioned portion of the tube tightly gripping the adjacent portion of the coil spring, and a propeller having a lateral projection engageable between the coils of the coil spring to move the propeller longitudinally when the tip is rotated relatively to the barrel, the coil spring rearwardly of the collar being unattached to the tube, the unattached rear portion of the coil spring being free for resilient distortion should the lead propelling parts become jammed while the propeller projection is in engagement therewith, and means for holding the

propeller against rotation with relation to the barrel when the tip is rotated thereon.

5. A mechanical pencil comprising a barrel having a bore, a tip rotatably mounted on said barrel, said tip having a nose portion provided with a rearwardly extending collar, a tube extending longitudinally into the collar, a coil spring within the tube, said coil spring constituting a lead guide means the collar and those portions of the tube and coil spring within the collar being fixed to rotate together with the tip, the tube extending rearwardly from the collar and extending rotatably into the bore of the barrel, the coil spring extending rearwardly from the collar within the tube and unattached to the tube, and means for holding the propeller against rotation with relation to the barrel when the tip is rotated thereon, said tube having a longitudinal slit extending from the collar to and through the free end of the tube.

6. A mechanical pencil comprising a barrel having a bore, a tip rotatably mounted on said barrel, said tip having a nose portion provided with a rearwardly extending collar, a tube extending longitudinally into the collar, a coil spring within the tube, the collar and those portions of the tube and coil spring within the collar being fixed to rotate together with the tip, the tube extending rearwardly from the collar and extending rotatably into the bore of the barrel, the coil spring extending rearwardly from the collar within the tube and unattached to the tube, the collar being forced inwardly to grip the tube, and the tube being forced inwardly to grip the coil spring, and means for holding the propeller against rotation with relation to the barrel when the tip is rotated thereon.

7. A mechanical pencil comprising a barrel having a bore, a tip rotatably mounted on said barrel, said tip having a nose portion provided with a rearwardly extending collar, a tube extending longitudinally into the collar, a coil spring within the tube, the collar and those portions of the tube and coil spring within the collar being fixed to rotate together with the tip, the tube extending rearwardly from the collar and extending rotatably into the bore of the barrel, the coil spring extending rearwardly from the collar within the tube and unattached to the tube, that portion of the tube normally within the barrel having a longitudinal slit, the portion of the tube on the side of the slit pressing outwardly against the wall of the bore of the barrel to removably and rotatably hold the tube in the barrel, and means for holding the propeller against rotation with relation to the barrel when the tip is rotated thereon.

8. In a mechanical pencil a barrel having a bore, a tip rotatably and removably mounted on the barrel, the tip having a hollow cylindrical portion, a tube in said cylindrical portion and extending rearwardly a substantial distance therefrom, a coil spring within the tube, the cylindrical portion being fixed to the tube, and the tube being fixed to the coil spring adjacent the outer end portion of the latter, the remainder of the coil spring being unattached to the tube, a propeller longitudinally movable in the coil spring, a projection on the propeller normally engaging the trackway between the coils of the coil spring, that portion of the coil spring unattached to the tube being yieldable longitudinally to prevent breakage of parts should the lead propelling mechanism become jammed.

9. In a mechanical pencil a barrel having a

bore, a tip rotatably and removably mounted on the barrel, the tip having a hollow cylindrical portion, a tube in said cylindrical portion and extending rearwardly a substantial distance therefrom, a coil spring within the tube, the cylindrical portion being fixed to the tube, and the tube being fixed to the coil spring adjacent the outer end portion of the latter, the remainder of the coil spring being unattached to the tube, a propeller longitudinally movable in the coil spring, a projection on the propeller normally engaging the trackway between the coils of the coil spring, that portion of the coil spring unattached to the tube being yieldable longitudinally to prevent breakage of parts should the lead propelling mechanism become jammed, the rearwardly extending portion of the tube entering the bore of the barrel and having a rotatable and longitudinal removable friction grip therein.

10. In a mechanical pencil a barrel having a bore, a tip rotatably and removably mounted on the barrel, the tip having a hollow cylindrical portion, a tube in said cylindrical portion and extending rearwardly a substantial distance therefrom, a coil spring within the tube, the cylindrical portion being firmly secured to the tube, and the tube being firmly secured to the coil spring adjacent the outer end portion of the latter, the remainder of the coil spring being unattached to the tube, a propeller longitudinally movable in the coil spring, a projection on the propeller normally engaging the trackway between the coils of the coil spring, that portion of the coil spring unattached to the tube being yieldable longitudinally to prevent breakage of parts should the lead propelling mechanism become jammed, said tube having an open ended longitudinal slit in one side and a closed ended longitudinal slit in its opposite side, said rearwardly extending portion of the tube entering the bore of the barrel, the portions of the tube along the sides of the slits affording a friction grip of the tube within the bore of the barrel.

11. In a mechanical pencil a barrel having a bore, a tip rotatably and removably mounted on the barrel, the tip having a hollow cylindrical portion, a tube in said cylindrical portion and extending rearwardly a substantial distance therefrom, a coil spring within the tube, the cylindrical portion being firmly secured to the tube, and the tube being firmly secured to the coil spring adjacent the outer end portion of the latter, the remainder of the coil spring being unattached to the tube, a propeller longitudinally movable in the coil spring, a projection on the propeller normally engaging the trackway between the coils of the coil spring, that portion of the coil spring unattached to the tube being yieldable longitudinally to prevent breakage of parts should the lead propelling mechanism become jammed, the rearmost coil of the coil spring being open and terminating in a free end to guide the propeller projection into the spiral space between the coils of the coil spring upon the insertion of a new lead.

12. In a mechanical pencil a barrel having a bore, a tip rotatably and removably mounted on the barrel, the tip having a hollow cylindrical portion, a tube in said cylindrical portion and extending rearwardly a substantial distance therefrom, a coil spring within the tube, the cylindrical portion being rigidly fixed to the tube, and the tube being rigidly fixed to the coil spring adjacent the outer end portion of the latter, the remainder of the coil spring being unattached to

the tube, a propeller longitudinally movable in the coil spring, a projection on the propeller normally engaging the trackway between the coils of the coil spring, that portion of the coil spring unattached to the tube being yieldable longitudinally to prevent breakage of parts should the lead propeller mechanism become jammed, the tube and coil spring also extending a distance forwardly of the hollow cylindrical portion.

13. In a mechanical pencil, a barrel having a bore, a tip rotatably and removably mounted on the barrel, an open ended tube fixed to the tip, a coil spring within the tube and fixed near one end thereto and otherwise unattached to the tube, said coil spring constituting a lead guide means, the tube rotatably and removably extending into the bore of the barrel, and a propeller having a projection engageable with the coils of the coil spring, the tube having on one side a longitudinal slit extending from the collar to and through the free end of the tube, and on the other side a shorter slit having closed ends.

14. A mechanical pencil comprising a barrel having a bore, a tip rotatably and removably mounted on the barrel, the tip having an upper plastic portion and metallic nose portion, said nose portion at its upper end having a rearwardly extending tubular collar and in its forward portion a hollow interior, a thin metallic tube extending through the collar and contacting said hollow interior, said tube also extending rearwardly into the bore of the barrel, a coil spring in the tube and extending approximately the length thereof, said collar having a radially pressed gripping engagement with the tube, and that portion of the tube within the collar having a radially pressed gripping engagement with the adjacent portion of the coil spring, the coil spring otherwise being unattached to the tube so that its rear portion will be freely yieldable longitudinally and have spaces between the coils to hold lead dust, a propeller having a lateral projection engageable with the coils of the coil spring, said tube having an open ended longitudinal slit in one side and a closed ended longitudinal slit in the opposite side, said slits affording a frictional grip between the tube and the bore in the barrel, said yieldable rear portion of the coil spring affording a cushioning action to prevent breakage of parts should the lead propelling mechanism become jammed, and means for holding the propeller against rotation with relation to the barrel when the tip is rotated thereon.

15. The method of producing tips for mechanical pencils, which consists in forming a metallic nose portion to have a cylindrical collar, forming from thin metal a tube having a longitudinal slit extending from end to end through one side wall, forming a shorter, closed ended slit through the opposite side wall, placing an open ended coil spring within said tube, positioning the assembled coil spring and tube within the collar with a considerable portion of the tube and coil spring extending rearwardly from the collar, and swaging the collar against the tube and the tube against the adjacent portion of the coil spring and causing the coils of the coil spring to bite into the tube for that portion within the collar, leaving the rearwardly extending portion of the coil spring yieldably movable longitudinally of the tube.

16. The method of producing tips for mechanical pencils, which consists in forming a metallic nose portion to have a cylindrical collar, forming from thin metal a tube having a longitudinal

slit extending from end to end through one side wall, forming a shorter, closed ended slit through the opposite side wall, placing an open ended coil spring within said tube, positioning the assembled coil spring and tube within the collar with a considerable portion of the tube and coil spring extending rearwardly from the collar, and swaging the collar against the tube and the tube

against the adjacent portion of the coil spring and causing the coils of the coil spring to bite into the tube for that portion within the collar, leaving the rearwardly extending portion of the coil spring yieldably movable longitudinally of the tube, and molding hardenable plastic material over the swaged collar and portion of the tube.

FRANK C. DELI.
